(57) **CLAIM**

The ornamental design for a roof structure for automobile or replica thereof, as shown and described.

DESCRIPTION

FIG. 1 is a left side elevation view of a roof structure for automobile or replica thereof in accordance with the present design, the right side elevation view thereof being a mirror image of the left side elevation view;

FIG. 2 is a rear perspective view thereof;

FIG. 3 is a front perspective view thereof;

FIG. 4 is a top plan view thereof;

FIG. 5 is a rear elevation view thereof; and,

FIG. 6 is a front elevation view thereof.

The broken lines show portions of the roof structure for automobile or replica thereof and environment that form no part of the claimed design.

Any combination of the illustrated features may be claimed in this application or a continuing application claiming priority to this application by converting any of the solid lines to broken lines, any of the broken lines to solid lines, or any combination thereof.
